UNITED STATES PATENT OFFICE.

JUDSON M. GRIFFIN, OF DETROIT, MICHIGAN.

CHECK-PROTECTOR.

No. 857,618.

Specification of Letters Patent.

Patented June 25, 1907.

Application filed February 9, 1907. Serial No. 356,532.

To all whom it may concern:

Be it known that I, JUDSON M. GRIFFIN, a citizen of the United States, residing at Detroit, county of Wayne, State of Michigan, have invented a certain new and useful Improvement in Check-Protectors; and I declare the following to be a full, clear, and exact description of the same, such as will enable others skilled in the art to which it pertains to make and use the same, reference being had to the accompanying drawings, which form a part of this specification.

This invention relates to check protectors, and has for its object an improved device of simple construction and easy of manipulation, whereby any part of an ordinary check in which writing occurs, either in figures or in full words, may, after the writing has been finished, have its paper mutilated or partially perforated, without impairing the legibility of the writing, so that erasure or alteration of the amount is rendered difficult, if not impossible.

In the drawings:—Figure 1, is a perspective of one form of the device. Fig. 2, is an end elevation, partly in section, of the same. Fig. 3, is a plan of a modified form. Fig. 4, is an end elevation of this form.

A part of the upper surface of the base 1 has preferably a special corrugated surface 2, and at one end of the base, shown in Fig. 1, is hinged a cover plate 3, which extends over its entire length, and whose center, which is designed to lie immediately over the corrugated part 2, is cut away to afford access thereto from above. At each side of the cover are guides or tracks 4 and 5, under whose overhanging inner edges 4^a and 5^a engage the ends of the journal pin or axle 6 on which is journaled a mutilating roller 9, which, when the cover is brought down against the base piece, engages closely with its corrugations against those of the piece 2. Any paper inserted therebetween is roughened in such a way that its fiber is grilled or embossed, and any attempt to alter the writing by further pen strokes results in a running of the ink through the broken fibers of the paper in a way that instantly destroys all negotiability of the check in the eyes of an experienced person.

If merely that portion of one line on which the amount of the check is written in figures is to be grilled, a short stroke of the handle 10 and the roller 9 is sufficient, but if, in addition, the entire line in which the amount is

written out at full length, or the line containing the name of the payee or that containing the signature of the maker is to be similarly protected, the pressure of the roller over 60 nearly the entire length of the corrugated part 2 is necessary.

In Figs. 3 and 4, is illustrated a type of this device in which the hinging of the roller-supporting portion to the base portion is 65 along a side, instead of one end. The slide rod 11 is supported between the inclined supports 12 and the bracket 13 is slidably journaled thereon, and its possible range of movement limited accordingly. The modification 70 in the form of the casing 14 here used from the type shown in Figs. 1 and 2, is seen to be comparatively slight. In this type the holding effect on the check of the cover plate 2, (which as such is omitted), is taken by leaf 75 springs 15 at each end of the base, under which the check is slipped to the position desired before the roller is applied.

What I claim is:—

1. In combination with a base having a 80 grilled upper surface, means hinged thereto for holding a paper in place thereupon, said means being wholly free from interfering engagement over the grilled portion, and a grilled roller adapted to be moved lengthwise 85 of the grilled surface, being guided within and confined to a path complementary in extent therewith, substantially as described.

2. In a check protector, in combination with a grilled base, a mutilating roller adapted to coact therewith in mutilating a sheet of paper inserted therebetween, means hinged to the base for holding the paper in place, and a guide member whereby the possible range of movement of the roller is limited, 90 substantially as described.

3. A check protector, having in combination with a mutilating roller, a base portion adapted to support the check and to co-operate with the roller in the mutilation of selected portions of its surface, means hinged to that part of the base portion whose surface is not pressed upon by said roller for holding the check in place during the movement of the roller thereover, and means adapted to 100 confine and guide the travel of the roller, substantially as described.

4. In a check protector, the combination of a base having a portion of its upper surface roughened, a roller having a mutilating periphery adapted to travel thereover, and a frame portion hinged thereto and adapted by 110

pressure thereagainst to hold a check in position over the roughened portion of the surface, though out of interfering position with the access thereto from above and to serve as a confining guide-way for the trayel of the roller over the roughened portion of the base, substantially as described.

In testimony whereof, I sign this specification in the presence of two witnesses.

JUDSON M. GRIFFIN.
